(57) **CLAIM**

The ornamental design for a cooling device, as shown and described.

DESCRIPTION

FIG. 1 is a front perspective view of a cooling device in accordance with the present invention;
FIG. 2 is a front view thereof;
FIG. 3 is a back view thereof;
FIG. 4 is a left side view thereof;
FIG. 5 is a right side view thereof;
FIG. 6 is a top view thereof;
FIG. 7 is a bottom view thereof; and,
FIG. 8 is a back perspective view thereof.

The broken line showing of the cooling device is for the purpose of illustrating portions of the "article" and forms no part of the claimed design.
